[57] CLAIM

The ornamental design for a data processing equipment unit, as shown and described.

DESCRIPTION

FIG. 1 is a front, top, left side perspective view of a data processing equipment unit showing my new design with the support feet forming no part of the claimed design and being shown in broken lines for illustrative purposes only;
FIG. 2 is a front elevational view thereof;
FIG. 3 is a right side elevational view thereof;
FIG. 4 is a left side elevational view thereof;
FIG. 5 is a top plan view thereof;
FIG. 6 is a bottom plan view thereof; and,
FIG. 7 is a rear elevational view thereof.
